UNITED STATES PATENT OFFICE.

LEONARD AITKEN, OF LAWRENCE, MASSACHUSETTS, ASSIGNOR TO LAWRENCE DUCK COMPANY, OF LAWRENCE, MASSACHUSETTS, A CORPORATION OF MASSACHUSETTS.

WEFT-REPLENISHING LOOM.

1,375,886.

Specification of Letters Patent. Patented Apr. 26, 1921.

Application filed April 13, 1914, Serial No. 831,355. Renewed October 13, 1919. Serial No. 330,528.

To all whom it may concern:

Be it known that I, LEONARD AITKEN, a citizen of the United States, and resident of Lawrence, in the county of Essex and State 5 of Massachusetts, have invented certain new and useful Improvements in Weft-Replenishing Looms, of which the following is a specification.

This invention relates to weft-replenishing looms, and comprises improvements in the weft-replenishing mechanism.

Briefly stated, an object of the invention is to provide improved and more efficient mechanism in looms of the type disclosed in Barr 15 ell Patents 1,207,124, granted December 5, 1916 and 1,221,410, granted April 3, 1917.

Of the accompanying drawings:

Figure 1 (Sheet 1) represents an end elevation of a loom, omitting elements which 20 are not necessary to illustrate the invention.

Fig. 2 is an end elevation of the shuttle support on which the shuttle rests while being loaded.

Fig. 3 is a vertical cross section through 25 the shuttle support shown by Fig. 2 and through the carrier by which the shuttle is transferred to the shuttle box of the lay, the carrier being about to remove the loaded shuttle from the loading support.

Fig. 4 (Sheet 2) is a top plan view of the 30 change end of the lay, and includes a portion of the shuttle-ejector and the shuttle binder represented by dotted lines.

Fig. 5 represents a top plan view of the 35 shuttle receiver to which the spent shuttle is transferred by the ejector.

Fig. 6 represents a top plan view of the 40 carrier which transfers the spent shuttle from the receiver shown by Fig. 5 to the loading support shown by Figs. 2 and 3 and which transfers the loaded shuttle from the loading support to the shuttle box of the lay.

Fig. 7 is a vertical cross section through 45 the shuttle box of the lay, the shuttle carrier, and the shuttle receiver.

Fig. 8 is a vertical cross section similar to Fig. 7, showing the parts in a different position.

Fig. 9 is a vertical cross section through 50 the shuttle box of the lay and through the mechanism associated therewith.

Fig. 10 is a cross section similar to Fig. 9, showing the parts in another position.

Fig. 11 (Sheet 3) is an elevation of the

bobbin magazine and loading support as 55 viewed from the rear.

Fig. 12 is a top plan view, partly in section, of the loading mechanism.

Fig. 13 is an end elevation of a portion of the loom frame, and includes parts of the 60 loading mechanism.

Fig. 14 is an end elevation of the elements included in Fig. 11.

Fig. 15 is an end elevation, on a larger scale, of the shuttle support included in 65 Fig. 14. In Fig. 15 the bobbin thread leading from the bobbin in the shuttle is depressed by an arm into a thread-receiving eye in the shuttle support.

Fig. 16 is an elevation similar to Fig. 15, 70 showing the loaded shuttle removed from the support as if being transferred to the shuttle box, the bobbin thread being caught by a hook to effect the threading of the shuttle while it is moving toward the shuttle 75 box.

Fig. 17 (Sheet 4) is a top plan view of the loading support and a loaded shuttle therein.

Fig. 18 is a front elevation, on a larger scale, of one end of a shuttle. 80

Fig. 19 is a vertical section in a plane from front to rear through the shuttle support and shuttle as shown by Fig. 17. This figure illustrates a cutting device by which the weft end of the spent bobbin is severed. 85

Fig. 20 is a diagram representing in plan view a spent bobbin, the cutting device and the adjacent selvage of the woven fabric,—the relation indicating the relative positions when the spent bobbin is about to be ejected 90 from the shuttle resting upon the loading support.

Fig. 21 (Sheet 1) is a section through the structure intersected by line c—c of Fig. 1.

This loom employs two shuttles and a 95 bobbin magazine. The shuttles are used alternately and are interchanged by suitable automatic mechanism as often as it is necessary to replenish the weft. When a change of shuttles is required, the weaving mechanism is automatically stopped by suitable well-known stop mechanism and the power is connected to the shuttle-changing mechanism. The latter transfers a loaded shuttle from the loading support to the shuttle box 100 of the lay and transfers the spent shuttle to the loading support. When the shuttles have been interchanged, the power is auto- 105

matically disconnected from the shuttle-changing mechanism and is connected to the weaving mechanism, whereupon the loom resumes weaving. While the spent shuttle rests upon the loading support, suitable loading mechanism is automatically operated to transfer a bobbin from the bobbin magazine to the spent shuttle. I employ a bobbin magazine and shuttles similar to the well-known Northrop magazine and shuttle. I have not shown the automatic stop mechanism nor the clutch mechanism by which the power is disconnected from the weaving mechanism and connected to the shuttle-changing mechanism, and vice versa, as any mechanism suitable for this purpose, such as that used by the looms built by the Stafford Company, of Readville, Massachusetts, may be employed.

The main frame members of the loom are indicated at 20, 20; and the crankshaft 21, connecting-rod 22, lay 23, swords 24, and rockshaft 25 are all arranged according to the well-known practice. A cam shaft 26 carries the several cams which operate the shuttle-changing mechanism. This cam shaft remains stationary while the crankshaft 21 is rotating, but is driven by the aforesaid automatic clutch mechanism when the crankshaft comes to rest. When the cam shaft has completed its cycle, the clutch mechanism automatically disconnects the power from the cam shaft and connects it to the crankshaft. For this purpose the cam shaft is provided with a cam 27 which acts upon a lever 28 to move a starting rod 29 in the direction indicated by an arrow in Fig. 1. The rod 29 is pivotally connected to an arm 30 which is affixed to a rockshaft 31. The rockshaft extends from the change end of the loom to the opposite end where the clutch mechanism is located. The elements of the starting mechanism which are illustrated are similar to those of the Stafford loom hereinbefore mentioned, and as the operation is like that of the Stafford loom, further description will not be necessary.

The two shuttles are indicated respectively at α and α' . When the condition of the weft in the operating shuttle requires a change of shuttles, the automatic stop mechanism causes the weaving mechanism of the loom to come to rest when the operating shuttle is in the shuttle box at the change end of the lay and when the lay is in the position shown by Fig. 1. At this time the elements which form the shuttle box at the change end are in the position shown by Fig. 9, excepting that this figure is set so that the top surface of the lay is horizontal, instead of inclined as shown by Fig. 1. It is to be understood that the horizontal arrangement as shown by Figs. 7, 8, 9 and 10 is shown merely for the purpose of facilitating the drawing of the figures.

The shuttle α as shown by Fig. 9 is between the shuttle binder 32 and a movable shuttle-box front 33. In due course the member 33 is raised to permit an interchanging of shuttles. (See Fig. 10.) It is carried by arms 34 which are mounted upon a pivot 35. An arm 36, rigidly related to the arms 34, is connected by a rod 37 to a lever 38 which is actuated by a cam 39. The fulcrum of the lever is indicated at 40. A spring 41 (Fig. 1) connected to one of the arms 34 exerts a downward pull to return the shuttle-box front 33 to shuttle-engaging position when the cam 39 permits such return.

After the lower edge of the front 33 has risen above the top of the shuttle α , it operates an ejector 42 by which the shuttle is moved forward to a receiver 43. Although the upward movement of the front 33 is positive, the ejecting movement of the ejector is yielding as the result of providing yielding means for transmitting movement from the front 33 to the ejector. My purpose in providing yielding means is to avoid injuring the shuttle in case the shuttle should become caught. The ejector is affixed to an arm 44 which is mounted to swing upon a pivot 45. A separate piece 46 is arranged upon the pivot 45 in position to be engaged by a cam surface 33' on the front 33. The member 46 is movable relatively to the arm 44, and ejecting movement is transmitted from the one to the other by a compression spring 47. This spring is disposed between ears 48 and 49 formed respectively on the members 46 and 44. A bolt 50 extends loosely through the ears and through the spring, and is provided with a nut 51 whereby the ears are prevented from being separated too far by the spring 47. The bolt serves to determine the normal adjustment of the members 44 and 46. A coil-spring 52 is arranged to engage the arm 44 for the purpose of retracting the ejector. The operating cam 39 is so formed that the front 33 rises continuously until it reaches its highest position, thereby imparting ejecting movement to the ejector, and the cam then permits the front 33 to descend part way so as to permit the spring 52 to retract the ejector. The front 33, however, is held at its intermediate position for a sufficient period of time to permit the approaching loaded shuttle to pass under it. The front 33 is thereafter permitted to descend to its initial position.

Referring to Figs. 9 and 10, the cam surface 33' causes a diminution in the speed of the ejector 42. An arrow in Fig. 9 indicates the point of the cam 33' which first touches the tip of the piece 46. The point of contact changes as the ejector moves forward, because the cam member and piece 46 swing about different axes. The reason

for retarding the movement of the ejector is to avoid throwing the ejected shuttle with too great force against the receiver 43. It is desirable to eject the shuttle as quickly as possible in order to give the other elements sufficient time in which to operate, and for this reason the ejector is arranged to be moved rapidly at first. The shuttle is thus transferred quickly to the receiver, and, since the rate of the ejecting movement diminishes, the tendency to cause a rebound of the shuttle is avoided.

The receiver 43 for the ejected shuttle is shown in plan by Fig. 5. In its initial position its shuttle-supporting surface is substantially flush with the top surface of the shuttle box. The receiver, after receiving the spent shuttle, is raised above the path of the approaching loaded shuttle, and while the shuttle carrier hereinafter described is against the shuttle box the receiver 43 descends to deposit the spent shuttle upon the carrier. The receiver is so formed that it engages the shuttle only at the ends and provides a suitable space for the reception of the shuttle carrier. The receiver (see Fig. 5) is provided with substantially vertical flanges 53 which are arranged in guides 54 carried by the shuttle box. A plunger 55 is affixed to the receiver and extends downwardly through a guide 56 carried by the lay and through a guide 57 carried by the rockshaft 25 on which the swords are mounted. A compression spring 58 coiled about the plunger normally depresses the same to hold the shuttle-supporting surface of the receiver flush with the shuttle-supporting surface of the shuttle box. This spring, as shown, is disposed between the guide 56 and a collar 59 which is affixed to the plunger. The receiver is raised by a lever 60 and cam 61. The fulcrum of the lever is at 40, and the free end of the lever (see Fig. 1) is arranged between two ears 62 which are formed upon the collar 59. The lifting surface 63 of the lever is substantially concentric with relation to the axis about which the lay swings, so that the lever and collar will always be in coöperative relation, notwithstanding the oscillatory movement imparted to the collar by the forward and back movement of the lay. As shown by Figs. 4 and 5, the shuttle box is provided with recesses 64, and the receiver is provided with lips 65 arranged to occupy said recesses. When the receiver is in shuttle-receiving position, as shown by Figs. 1, 9 and 10, the lips 65 rest upon the bottoms of the recesses 64, and the shuttle-supporting surfaces of the shuttle box and receiver are thus caused to be substantially flush.

The shuttle carrier is indicated at 66. It is affixed to the upper end of a lever 67 whose fulcrum is at 68. The carrier is moved to the rear by a spring 69 and is

moved toward the front by a cam 70. The cam engages a roll 71 carried by the lever 67. The carrier has shuttle-supporting portions 72, 72 and shuttle-supporting portions 73, 73. The portions 72 carry the spent shuttle to the loading support hereinafter described, and the portions 73 carry the loaded shuttle to the shuttle box. The carrier is provided with a movable shuttle-engaging member 74 which is mounted upon a pivot 75. One function of the member 74 is to hold the loaded shuttle so securely that it cannot slip from the desired position on the supporting portions 73 while being transferred to the shuttle box. Another function of the member 74 is to hold the spent shuttle securely in the desired position upon the portions 72. The member 74 is provided with tongues 76 which are arranged to hook under the lower edge of the shuttle and occupy the chamber in which the bobbin *a* is carried. (See Fig. 7). Recesses 77, shown best by Fig. 4, are formed in the shuttle-supporting surface of the shuttle box to receive the tongue 76 as shown by Fig. 7. The carrier remains stationary for a brief period while the receiver 43 descends to deposit the spent shuttle *x* upon the shuttle-supporting portions 72. The spent shuttle is deposited between upwardly extending lips 79 of the carrier and upwardly projecting portions 80 of the shuttle retainer 74. After the spent shuttle has been deposited upon the portions 72, the shuttle-box front 33 descends to the position shown by Fig. 8. The member 33 in descending engages the portions 80 and depresses the tongues 76 below the bottom of the loaded shuttle *x* (see Fig. 8), the recesses 77 being sufficiently deep for this purpose. At the same time, the shuttle-box front 33 forces the spent shuttle *x* against the lips 79. For this purpose the member 33 is provided with cam surfaces 81. The lower edge of the member 33 is now below the top of the loaded shuttle, and is therefore in position to keep the loaded shuttle in the shuttle box when the shuttle carrier is retracted from the lay. Cam 70 now acts to move the shuttle carrier to transfer the spent shuttle *x* to the loading support. When the projecting portions 80 of the shuttle retainer escape from the lower edge of the shuttle-box front 33, a spring 82 swings the shuttle retainer upwardly until the latter strikes the body of the carrier indicated at 66. The projecting portions 80 are thus placed in position to keep the spent shuttle against the lips 79. The shuttle box front 33, upon being released by the portion 80, springs back to its initial position, shown by Fig. 9.

The loading support, upon which the spent shuttle rests while receiving a full bobbin, is shown best by Figs. 11 and 17

and is indicated at 83. It is formed to provide a space 84 through which the carrier passes and through which the spent bobbin α^5 drops when the latter is discharged from the bottom of the shuttle. The loading support, as shown, is affixed to the breast-beam 85. The spent shuttle travels forward on the carrier until its front side strikes an abutment 86 which forms a part of the loading support. The carrier, however, continues to move forward until the substantially vertical faces 87 of the retainer 74 (see Fig. 6) have passed beyond the front side of the shuttle. The shuttle retainer 74 escapes from the spent shuttle in consequence of being depressed by the shuttle. When the projections 80 have passed beyond the shuttle, the retainer 74 is again raised by its spring 82.

20 Following an interchange of shuttles the weaving mechanism is set in operation and the spent shuttle resting on the loading support 83 is loaded with a full bobbin. The loading mechanism has not as yet been described. When the shuttle carrier is moved to transfer a loaded shuttle from the loading support to the shuttle box (see Fig. 3), the faces 87 of the shuttle retainer 74 push against the front side of the loaded shuttle and thus move the shuttle toward the shuttle box. The loaded shuttle is lifted from the loading support 83 by the supporting portions 78 of the carrier, the front wall of the shuttle thus entering the grooves 88 (Fig. 6) between the abutments 87 and the retaining tongue 76.

The bobbin magazine is indicated as a whole at 90. As previously stated, this magazine is in general similar to the well-known bobbin magazine of the Northrop loom. It has a rotatable element 91 by which the full bobbins α are supported in a circular series. The rotatable element is rotated step by step to arrange the bobbins successively in preliminary loading position, as shown by Figs. 11 and 13, from which position they are depressed by a loader 92. Although the operation of the Northrop magazine and the shuttle structure are well known, it may be well to state that when a full bobbin is transferred from the magazine to the shuttle the full bobbin depresses the empty bobbin and the latter is discharged from the bottom of the shuttle. The loader 92 as used in the Northrop loom is depressed positively; but according to my invention it is depressed by yielding mechanism which is designed to avoid breaking the loader and other elements whenever the loading movement is unduly opposed from any cause, such for example as an incorrect position of the shuttle resting upon the loading support. The loading arm 92 is arranged upon a pivot 93 which is affixed to the frame 90 of the magazine. A coil-spring 94 is ar-

ranged to normally raise the loading arm. An actuating arm 95 is rigidly related to the loading arm 92, the two arms being connected in the present instance by a portion indicated at 96 in Figs. 12 and 13. An arm 97 is loosely mounted upon the pivot 93 and is connected with the arm 95 by a tension spring 98. The arm 97 has an abutment 99 against which the arm 95 is normally held by the spring 98. When the arm 97 is moved in the direction indicated by an arrow in Fig. 13, its movement is transmitted by the spring 98 to the arm 95 of the loader, provided the loading movement of the loader is not unduly opposed. If the movement of the loader should be unduly opposed, the spring 98 will yield to permit the aforesaid movement of the arm 97.

As shown by Fig. 13, the lower end of the arm 97 is pivotally connected to the forward end of a member 100. The rear end of 85 100 is V-shaped and is adapted to occupy a V-shaped notch formed in a striker 101 which swings to and fro with the lay. Excepting as hereinafter specified, the member 100, according to the present arrangement of mechanism, remains in the position shown by full lines in Fig. 13. It is supported in this position by an offset member 102 carried by a lever 103. The fulcrum of the 90 lever is at 104. The lower end of the lever is arranged to be engaged by a cam 105 carried by the cam shaft 26. While the member 100 remains in the position shown by full lines, it is out of the path of the striker 101. During the cycle of the cam shaft 26 the lever 103 is moved in the direction indicated by an arrow, and the member 102 is thus caused to swing the member 100 upwardly to the position indicated by dotted lines, the pointed end of the member 100 being thus placed in the path of the striker 101. A latch, indicated at 106, serves to support the member 100 in its raised position, until the member 100 is released as 110 hereinafter specified. A projection 107, shown in the form of a pin and carried by the member 100, co-operates with the latch. The latch is mounted upon a pivot 108 and is provided with a weight 109 which normally holds the latch against the rear side of the pin. During the cycle of the cam shaft 26 the pin is raised above the top of the latch, and the latch, being thus released, is moved by the weight 109 to the position 115 indicated by dotted lines. The lever 103 returns without pause to the position shown, but the pin 107 rests upon the upper end of the latch, thus supporting the member 100 in the path of the striker. When the weaving mechanism is subsequently set in operation, the striker engages the member 100 and imparts loading movement to the arm 97. The forward movement of the member 100 carries the pin 107 away from the latch; and 120 125 130

when the member 100 is released by the striker 101, the member 100 drops upon the member 102, the pin 107 at this time being in front of the latch. When the member 100 is moved to the rear by the returning spring 94 (Fig. 12) the pin 107 strikes the latch and moves the same from dotted line position to full line position, the parts thus assuming their initial position.

10 I have provided the loading mechanism with improved means for laying the weft end a' in the throat a^2 of the shuttle. The rotatable element of the magazine includes notched disks 110 and 111 across whose rims the weft ends are drawn as shown by Fig. 11. The weft ends are secured to a weft-end holder 112 in the well-known manner. The substantially horizontal stretches of the weft threads extending between the disks 110 and 111 are carried against a fixed abutment 113 which, as shown, is in the form of a pin and extends upwardly from the loading support. As each bobbin in the magazine is moved to preliminary loading position, its weft end stands above and substantially in vertical alignment with the throat of the shuttle. When the loading arm 92 is depressed to transfer a loaded bobbin from the magazine to the shuttle, an arm 114 engages and depresses the stretch of weft thread which is between the disks 110 and 111. The arm 114 is carried by the loading arm 92, the arrangement being shown best by Fig. 12. As shown by Fig. 15, the upper edge of the end wall 115 of the loading support is below the top of the shuttle. This arrangement is to enable the weft thread to enter the throat of the shuttle while the shuttle is upon the loading support. When the arm 114 depresses the weft thread, the pin 113 guides the thread to the throat 116 and into the eye 117 of a thread holder 118. The thread is then retained in the eye by a hook 119. When the arm 114 rises, the thread is held by the hook 119. The holder 118 is set into the end wall 115. A movable thread hook 119' is affixed to a rockshaft 120 whose bearing is provided by a bracket 121 formed upon the loading support. The rockshaft carries also a shuttle-retaining member 122 whose function is to hold the shuttle against the abutment 86 for loading, and until a subsequent change of shuttles is required. A spring 120' (Fig. 17) acts to depress the members 119' and 122 to the position shown by solid lines in Fig. 2, but they are raised and held by the shuttle carrier 66. For this purpose the rockshaft 120 is provided with an arm 123 which is arranged to be engaged by the under side of the shuttle carrier when the carrier is moving toward the front of the loom. While the carrier remains in its foremost position it engages the arm 123 and thus locks the member 122 in shuttle-engaging position. When, however, the carrier moves to the rear to pick up the loaded shuttle, it releases the arm 123, whereupon the shuttle locking member 122 drops out of the path of the shuttle, and the thread-holder 119' at the same time carries the weft thread downwardly (see Fig. 16) to such position that the thread will be drawn farther into the throat of the shuttle as the shuttle moves toward the shuttle box. The weft thread is thus carried into the throat of the shuttle, sufficiently for weaving, before the shuttle reaches the shuttle box. It has been stated that the loaded shuttle passes under the raised shuttle-box front 33. In consequence of this operation, the weft thread extending from the loaded shuttle in the shuttle box to the thread holder 118 extends under the member 33, and when the latter drops to its normal position, as shown by Fig. 9, it depresses the underlying thread more firmly into the throat of the shuttle.

15 I have provided a device which is operated automatically to sever the weft thread of the spent bobbin at a point near the bobbin. This device is shown best by the figures on Sheet 4. At the right of Fig. 20 I have represented conventionally a small fragment of the woven fabric d . The weft thread running from the fabric to the spent bobbin a^5 is indicated at a^6 . This thread, of course, extends through the throat of the spent shuttle when the latter is deposited upon the loading support 88. The cutting device is indicated at 124 and is mounted upon the loading support. For convenience I have employed the well-known hand shears commonly used by weavers and have provided suitable mechanism for operating one of the shear blades 100 to sever the threads. As shown by Fig. 19, the shears 124 are arranged in a case 125, the latter being affixed to the loading support. The shears are made of a single piece of steel, and normally spring open. They are so arranged as to be open to receive the weft thread a^6 when the spent shuttle is traveling toward the loading support. The front side of the shuttle is provided with a socket 126 to receive the points 110 of the shears. This socket is close to the mouth of the throat a^2 (see Fig. 18) and is traversed by the weft thread which issues from the throat. When the empty shuttle 115 is being transferred from the shuttle box 120 to the loading support, the thread a^6 extends across the socket 126 in such position that it enters between the points of the cutting device. The continued forward movement of the shuttle carrier after the spent shuttle 125 has been deposited upon the loading support causes the cutting of the weft thread a^6 . The shuttle locking device 122, upon being moved to shuttle-locking position, acts upon a spring 127 which in turn acts 130

upon a member 128 which is loosely mounted upon the rockshaft 120. The member 128 has a finger 129 which is thus raised against the under side of the lower shear member 5 and the latter is raised to the position shown by Fig. 19 to sever the thread. Fig. 20 shows the relative positions of the cutting device and the spent bobbin. The thread a^6 is severed close to the mouth of the 10 throat a^2 before the loading mechanism has been operated to transfer a full bobbin to the spent shuttle. When the loading mechanism is subsequently operated, the spent bobbin upon being ejected carries with it 15 the short weft end which was formerly in the throat a^2 of the shuttle, thus clearing the throat for the reception of the new weft thread before the latter enters the throat.

I claim:

20 1. A weft-replenishing loom comprising in combination a movable bobbin magazine, a shuttle support, means arranged to move said magazine step by step to place the bobbins therein successively in a predetermined relation to said support, means movable with said magazine for carrying the weft ends of the bobbins, a thread-guide affixed to said support in the path of the weft-ends to register the latter relatively 25 to the throat of the shuttle, means arranged to transfer a bobbin from said magazine to the shuttle on said support, and means arranged to depress the registered weft end exteriorly of the shuttle, to move such weft 30 end in to the throat of the shuttle, said thread-guide being arranged to guide the weft end to the throat of the shuttle.

40 2. A shuttle-changing loom comprising in combination a movable shuttle-box front, means for moving the same to permit discharging the shuttle from the shuttle box, an ejector arranged to eject the shuttle from the shuttle box, and yielding means arranged to transmit movement from said shuttle-box front to said ejector to eject 45 the shuttle.

50 3. A weft-replenishing loom comprising, in combination, a lay and a change-shaft that operate alternately, a bobbin-magazine, a bobbin-engaging device arranged to transfer a full bobbin from said magazine to a shuttle, a member arranged to be movable to and from the path of the lay, means arranged to be actuated by said change-shaft 55 to move said member into the path of the lay to be moved by the latter, and means arranged to transmit to said bobbin-engaging device the movement that said member receives from the lay, whereby the operation 60 of said bobbin-engaging device is caused by the first beat of the lay following an operation of the change-shaft.

65 4. A shuttle-changing loom comprising in combination a movable shuttle-box front, means for moving the same from and to

shuttle-engaging position, shuttle-loading means arranged to put a full bobbin into a shuttle, a shuttle carrier, means arranged to transfer the spent shuttle from the shuttle box to said carrier, means carried by said shuttle-box front for engaging the shuttle on said carrier to locate the shuttle relatively to the carrier, and means for moving said carrier to transfer said shuttle to said loading means.

75 5. A shuttle-changing loom comprising in combination a movable shuttle-box front, means for moving the same from and to shuttle-engaging position, shuttle-loading means arranged to put a full bobbin into a 80 shuttle, a shuttle carrier having an abutment arranged to engage one side of the shuttle thereon, means arranged to transfer the spent shuttle from the shuttle box to said carrier, said shuttle-box front having a cam 85 surface arranged to force the shuttle laterally against said abutment, and means for moving said carrier to transfer said shuttle to said loading means.

90 6. A shuttle-changing loom comprising in combination a support for a loaded shuttle, a shuttle carrier and means for moving the same to transfer a loaded shuttle from said support to the shuttle box, and confronting abutments arranged on said carrier to engage opposite surfaces of the shuttle to prevent lateral movement of the shuttle relatively to the carrier.

95 7. A shuttle-changing loom comprising in combination a support for a loaded shuttle, 100 a shuttle carrier and means for moving the same to transfer a loaded shuttle from said support to the shuttle box, and a device arranged on said carrier to extend into the bobbin chamber of the shuttle to hold the 105 shuttle.

8. A shuttle-changing loom comprising in combination a support for a loaded shuttle, a shuttle carrier and means for moving the same to transfer a loaded shuttle from said 110 support to the shuttle box, and a device arranged on said carrier to engage the inner surface of the wall which forms the bobbin chamber of the shuttle, to hold the shuttle.

9. A shuttle-changing loom comprising in combination a support for a loaded shuttle, a shuttle carrier and means for moving the same to transfer a loaded shuttle from said support to the shuttle box, and a device 115 movably arranged on said carrier to engage and hold the shuttle.

10. A shuttle-changing loom comprising in combination a support for a loaded shuttle, a shuttle carrier and means for moving the same to transfer a loaded shuttle from said support to the shuttle box, and a device arranged on said carrier to extend 125 upwardly through the bottom of the shuttle to hold the shuttle.

11. A shuttle-changing loom comprising 130

- in combination a support for a loaded shuttle, a shuttle carrier and means for moving the same to transfer a loaded shuttle from said support to the shuttle box, a device movably arranged on said carrier to engage and hold the shuttle, and means arranged to move said device to release the shuttle.
12. A shuttle-changing loom comprising in combination a movable shuttle-box front and means for moving the same from and to shuttle-engaging position, a support for a loaded shuttle, a shuttle carrier and means for moving the same to transfer a loaded shuttle from said support to the shuttle box, and a shuttle-engaging device movably arranged on said carrier to keep the shuttle in place on said carrier, said device being arranged to be moved by said shuttle box front to release the shuttle.
13. A shuttle-changing loom comprising in combination a movable shuttle box front, a shuttle receiver adjacent the shuttle box, a shuttle-engaging member arranged to transfer the spent shuttle from the shuttle box to said receiver, means arranged to move said shuttle-box front to permit the shuttle to be transferred to said receiver, and means arranged to transmit movement from said shuttle-box front to operate said shuttle-engaging member, said means having provisions for causing an initially rapid and diminishing speed of transferring movement of said shuttle-engaging member.
14. A weft-replenishing loom comprising in combination a bobbin magazine, means arranged to transfer a full bobbin from said magazine to a shuttle, means arranged to depress the outlying bobbin thread upon the top of the shuttle and into a thread-holding device, said device being arranged to hold the thread against the top of the shuttle, whereby said thread is moved laterally into the throat of the shuttle when the shuttle is transferred to the shuttle box of the loom, and means arranged to transfer said shuttle to said shuttle box.
15. A weft-replenishing loom comprising in combination a bobbin magazine, a bobbin engaging member and its operating means arranged to transfer a full bobbin from said magazine to a shuttle, and a member carried by said bobbin-engaging member and arranged to engage the weft thread beyond the end of the shuttle and move the thread into the throat of the shuttle.
16. A weft-replenishing loom comprising in combination a bobbin magazine, a weft end holder, means arranged to transfer a full bobbin from said magazine to a shuttle, thread-engaging means arranged to move the weft thread into the throat of the shuttle, a thread guide arranged to guide the weft thread to said throat of the shuttle, and a thread hook arranged to engage the weft thread outside the shuttle to hold the weft thread in said throat, said thread-engaging means being arranged to move the thread into said hook.
17. A weft-replenishing loom comprising, in combination, a lay and a change-shaft that operate alternately, a bobbin-magazine, a bobbin-engaging device arranged to transfer a full bobbin from said magazine to a shuttle, a member arranged to be movable to and from the path of the lay, means arranged to be actuated by said change-shaft to move said member into the path of the lay to be moved by the latter, and yielding means arranged to transmit to said bobbin-engaging device the movement that said member receives from the lay, whereby the operation of said bobbin-engaging device is caused by the first beat of the lay following an operation of the change-shaft.
18. A shuttle-changing loom, comprising, in combination, a bobbin magazine, means for transferring a full bobbin from said magazine to a spent shuttle, means arranged to interchange the filled shuttle and a spent shuttle in the lay, and means arranged to sever the thread connecting the fabric and the spent bobbin at a point contiguous to the shuttle in which said spent bobbin is arranged.
19. A shuttle-changing loom, comprising, in combination, a bobbin magazine, means for transferring a full bobbin from said magazine to a spent shuttle, means arranged to interchange the filled shuttle and a spent shuttle in the lay, and means arranged to sever the thread of the spent bobbin while said bobbin is in the shuttle.
20. A shuttle-changing loom comprising, in combination a bobbin magazine, a support for supporting a shuttle adjacent said magazine for loading, means arranged to interchange a spent shuttle in the shuttle box of the loom and a filled shuttle on said support, means arranged to sever the bobbin thread leading from the spent bobbin in the shuttle on said support to the woven fabric in the loom, and means arranged to transfer a full bobbin from said magazine to the shuttle on said support.
21. A shuttle-changing loom comprising in combination shuttle-loading means arranged to put a full bobbin into a shuttle, a shuttle carrier having an abutment arranged to engage one side of a shuttle thereon, means arranged to transfer a spent shuttle from said shuttle box to said carrier, means arranged to force the shuttle against said abutment on said carrier, means carried by said carrier and arranged to keep the shuttle against said abutment, and means arranged to move said carrier to transfer the shuttle to said loading means.
22. A shuttle-changing loom comprising in combination shuttle-loading means ar-

ranged to put a full bobbin into a shuttle, a shuttle carrier, means arranged to move said carrier to transfer a loaded shuttle from said loading means to said shuttle box, means arranged to transfer a spent shuttle from said shuttle box to said carrier, means arranged to move said carrier to transfer the spent shuttle to said loading means, and shuttle-engaging means carried by said carrier and arranged to keep the loaded shuttle in one position on said carrier and to keep the spent shuttle in another position on said carrier.

23. A shuttle-changing loom comprising, in combination, shuttle-loading means for

putting a full bobbin into a shuttle, a shuttle-carrier having an abutment arranged to engage one side of a shuttle thereon, means for transferring a spent shuttle from the shuttle-box to said carrier, means arranged to force the shuttle against said abutment on said carrier, and means for moving said carrier to transfer said shuttle to said loading means.

In testimony whereof I have affixed my signature in presence of two witnesses.

LEONARD AITKEN.
